UNITED STATES PATENT OFFICE.

JOHN HENRY STONE, OF TORONTO, CANADA, ASSIGNOR TO MARIE LOUISE STONE, OF TORONTO, CANADA.

COMBINED HEATING AND COOKING OIL-STOVE.

SPECIFICATION forming part of Letters Patent No. 759,404, dated May 10, 1904.

Application filed March 31, 1903. Serial No. 150,357. (No model.)

To all whom it may concern:

Be it known that I, JOHN HENRY STONE, of the city of Toronto, in the county of York, in the Province of Ontario, Canada, have invented 5 certain new and useful Improvements in a Combined Heating and Cooking Oil-Stove, of which the following is a specification.

My invention relates to improvements in combined heating and cooking oil-stoves; and 10 the object of the invention is to produce a stove of this class which will generate a maximum amount of heat for a minimum amount of oil, and, further, to simplify the construction of the stove so as to adapt it for both 15 heating and cooking; and it consists, essentially, of a bowl having a bottomless tube extending through the center of the same and surrounded on the exterior within the bowl by copper and zinc members designed to be 20 immersed in the oil, burners supported in suitable necks and having substantially split tubular copper and zinc members designed to be 25 supported on the burners and having connected at the top the truncated-cone-shaped extensions and having extending outwardly therefrom flanges, a supporting-plate provided with 30 openings and a rim, the edge of such openings being designed to be supported on the flanges of the lower portions of the flues, a cylindrical casing supported on the rim of the 35 top plate, a top plate provided with cross-bars, a supplemental cylinder fitting the rim of the top plate and provided with a suitable top, and a plurality of sheet-metal rings extending 40 from the bottom of the supplemental casing to near the top thereof and located, preferably, concentrically one within the other, the parts being otherwise arranged and constructed in detail as hereinafter more particularly explained.

Figure 1 is a perspective exterior view of my improved stove. Fig. 2 is a vertical section through the stove. Fig. 3 is a detail of the copper and zinc members located outside of the central tube. Fig. 4 is a detail of the bottom plate of the stove. Fig. 5 is a detail

of the top plate. Fig. 6 is a detail of one of the radiating rings. Fig. 7 is a detail of the 50 burner and copper and zinc tubular members spring-held in the bottom of the same. Fig. 8 is a side elevation of the tubular member.

In the drawings like letters of reference indicate corresponding parts in each figure. 55

A is the base-bowl of the stove, which is provided with suitable legs *a*.

A' is the tube, which extends through the center of the bowl and is provided with the copper and zinc members *a'* and *a''*, a detail 60 of which is shown in Fig. 3.

B is the burner, which is suitably screwed into the neck *b* at the top of the bowl. I have shown four burners; but there may be a lesser or greater number, as desired. 65

C is a tube formed of copper and zinc members *c* and *c'*, the zinc member being innermost and as the tube is a split tube is bent outwardly at *c* *c'* at each side of the split over the outer copper member. 70

c is a rim or bead formed near the upper end of the split tube C. By pressing the tube together at the split it will be readily seen that it may be contracted in diameter, so as to fit and rest upon the shoulder *b'* at the bottom 75 of the burner B, and thereby maintain the tube in position.

The burner B is shown with a flat wick D; but this is not necessarily so, and such flat wick passes down through the tube C and is 80 necessarily curved as it passes through such tube to conform more or less to the contour of the tube, depending, of course, upon the width of the wick.

E represents reverse cone-frustum-shaped 85 flues, which fit on the top of the burner, as indicated, and E' represents the extensions of the tube, which are cone-frustum shaped and are bent around the upper flange *e* of the lower portion of the flue, as indicated, in order to 90 form a supporting-flange.

F is a plate provided with a series of openings *f* and a rim *f'*, located a little distance from the edge. The edges of the openings *f* are designed to be supported by the flanges *e*, 95 and thereby support the plate in position.

The plate F is provided with a central opening f^2 and perforations f^3 , as indicated, so as to permit of the upward passage of the cold air.

G is a cylinder which is fitted over the rim 5 f' and extends upwardly, as indicated.

H is a supplemental plate, which is provided with a depending flange h and a raised flange h' , having extending therebetween the cross-bar h^2 . The plate H is supported by the cylinder G and the flange h fits within the cylinder, as indicated.

I is a supplemental cylinder, which extends upwardly from the plate H, the bottom of the cylinder fitting snugly the flange h' on the outside.

J is the top, which may be of any ornamental design and perforated. The top J is connected by a central rod j to a bar or web j' , formed or secured within the cylinder I, secured to the bottom.

K represents a series of cylinders fitting one within the other and resting on the web j' and provided with turned - out projections k , which serve to maintain the cylinders equidistant apart or concentric to each other.

Having now described the principal parts involved in my invention, I shall briefly describe its utility. The central tube A', extending through the oil-bowl, will necessarily draw the cold air from the bottom of the stove once the burners are lighted and heats it as it ascends into the body of the stove. The members surrounding the tube, as well as the detachable tubes connected to the burner, serve to coat 35 with the chemicals contained in the oil and used in the deodorizing of the same to materially increase the heat from the flame of the burners. Whether it is by the gas generated thereby passing up to the wicks and burners 40 or from a battery formed I cannot say, but the result I have proved. Such heat passing upwardly through the flues E and E' and cylinder H into the radiating rings or cylinders K serves to produce an extremely high degree of 45 heat, which as far as I am aware has never been obtained in any other oil-stove.

If it is not desired to use the upper cylinder I, of course it may be removed and the bars h^2 may be used for cooking upon. I find in practice also that not only is the heat produced by the action of the tubes comprising the members as I have hereinbefore described, but that all smell from the oil is completely eliminated. The arrangement of the radiating cylinders or 55 rings is also very important, and I produce thereby a maximum radiation of heat for a minimum size of flame in the burners.

When I remove the upper cylinder I' for cooking purposes, I preferably substitute 60 therefor a cylinder of larger diameter, which is designed to extend upwardly around the cooking vessel, and by this means the heat instead of radiating is conserved and directed to the body of the vessel, thereby materially

increasing the heat and the rapidity with which 65 cooking may be done.

What I claim as my invention is—

1. In an oil-stove, the combination with the bowl and central air-tube extending upwardly through the same, and the burners suitably held in the top of the bowl and having the wicks extending thereinto, of the flues extending upwardly from the burners, and the cylinders supported on the flues and forming an air-chamber in communication with the flues and the central tube, as and for the purpose specified. 75

2. In an oil-stove, the combination with the bowl, the burners and wicks, and central tube extending through the bowl, of copper and zinc members surrounding such tube as and for the purpose specified. 80

3. In an oil-stove, the combination with the bowl, the burners and wicks and central tube extending through the bowl, of copper and zinc members surrounding such tube, and the split tube of copper and zinc members detachably connected to the bottom of the burners and through which the wicks extend as and for the purpose specified. 85

4. In an oil-stove, the combination with the burner, of a split tube of copper and zinc members provided with a bead or rim at the top designed to hold the split tube in position 90 in the burner, substantially as described. 95

5. In an oil-stove, the combination with the bowl, burners and reverse cone - frustum-shaped flues provided with a top flange and a cone-frustum-shaped extension held on such flange, of a plate having a series of openings, 100 the edges of which are supported on the flanges of the flues as and for the purpose specified.

6. In an oil-stove, the combination with the bowl, burners and reverse cone - frustum-shaped flue provided with a top flange and a cone-frustum-shaped extension held on such flange, of a plate having a series of openings, the edges of which are supported on the flanges of the flues, a central opening and perforations between the openings through which the flues extend, and an upwardly-extending rim, a cylinder supported on the rim, a top plate provided with a depending flange and having a central opening, an upwardly-extending flange and cross-bars extending across such opening as and for the purpose specified. 105 110 115

7. In an oil-stove, the combination with the bowl, burners and reverse cone - frustum-shaped flue provided with a top flange and a cone-frustum-shaped extension held on such flange, of a plate having a series of openings, the edges of which are supported on the flanges of the flues, a central opening and perforations between the openings through which the flues extend, and an upwardly-extending rim, a cylinder supported on the rim, a top plate provided with a depending flange and 120 125

having a central opening, an upwardly-extending flange and cross-bars extending across such opening, a supplemental cylinder supported on the top plate and provided with a 5 suitable top and bottom support, and a series of rings concentrically arranged one within the other and supported upon the bottom support as and for the purpose specified.

8. In combination in an oil-stove, a plurality of burners, a plurality of heating-flues independent of each other and extending up from the burners, and a heating-drum situated up above the said independent flues, and comprising within the same a plurality of concentric tubes open at both ends with means for supporting the same, substantially as described.

9. In an oil-stove, the combination with the bowl, burners and reverse cone-frustum-

shaped flue provided with a top flange and a 20 cone-frustum-shaped extension held on such flange, of a plate having a series of openings, the edges of which are supported on the flanges of the flues, a central opening and perforations between the openings through which 25 the flues extend, and an upwardly-extending rim, a cylinder supported on the rim, a top plate provided with a depending flange and having a central opening, an upwardly-extending flange and cross-bars extending across 30 such opening and a supplemental cylinder supported on the top plate designed to surround the cooking utensil as and for the purpose specified.

JOHN HENRY STONE.
